UNITED STATES PATENT OFFICE.

RICHARD C. YATES, OF BUFFALO, NEW YORK.

INTERNAL-COMBUSTION ENGINE.

Application filed August 3, 1918. Serial No. 248,093.

To all whom it may concern:

Be it known that I, RICHARD C. YATES, a citizen of the United States, residing at Buffalo, in the county of Erie and State of New York, have invented certain new and useful Improvements in Internal-Combustion Engines, of which the following is a specification.

This invention relates to internal combustion engines of the multiple-cylinder type, and more particularly to valve construction and means for actuating the same. It furthermore relates to arrangement and reduction of parts of such engines, and to improved port construction.

The object of my invention is to provide improved means for actuating the valves and means for lubricating said driving mechanism and also means for continuously cooling the lubricant. A further object of my invention is to provide a construction which contains a minimum number of moving parts and in the most compact form, and furthermore, to provide an engine of the multiple-cylinder type adapted to vehicular use and particularly to airplane use.

Referring to the drawings herewith, Fig. 1 is a side elevation of an engine embodying my improvements. Fig. 2 is a longitudinal central section. Fig. 3 is a top plan view. Fig. 4 is a horizontal section on the line $x-x$ of Fig. 2. Fig. 5 is a similar section on the line $y-y$ of Fig. 2. Fig. 2 is a detail on the line $z-z$ of Fig. 2.

The main casting 1 contains the cylinders 2 which are water-jacketed in the usual manner within which the pistons 3 reciprocate. The crank shaft 4 is journaled in a crank casing 5 and is connected to the pistons 3 by piston rod 6. The upper portion of the main casting 1 have the valve extensions 7 and the internal crowns 8 which carry the spark plugs, and said external sleeve portions and said crown portions form annular spaces to receive the rotating valves 9.

I will first describe the means for rotating the sleeve valves 9.

Upon their upper ends are gears 10 which may be either integral therewith or secured thereto, and which may be helical gears, as shown, or other desired type. By referring to Fig. 4 it will be seen that these gears 10 constitute two sets of train gears extending both ways from the center line of the engine, and that the two gears 10 nearest the central line of the engine mesh with a driving gear

11 which is mounted upon a vertical shaft 12, and which said vertical shaft is properly journaled more particularly as hereafter described. The sleeve valves 9 are windowed apertured to register with the inlet and exhaust ports at the proper intervals as hereafter more fully described. The shaft 12 extends downwardly into the crank casing and upon its lower end connects with an oil pump 13 of any desired type. The central bearing of the crank shaft 4 is a split-bearing comprising the two members 14 and 15, and mounted upon the crank shaft 4 between these two members 14 and 15 is a worm 16 which meshes with a gear 17 which is rigidly mounted upon the shaft 12.

It will now be seen that the crank shaft through said worm and gear and the shaft 12 drives the gear 11 which is in mesh with the oppositely disposed train gears 10. By this construction, communicating the power from the central point of the crank shaft upwardly and centrally through the engine to the oppositely disposed train gears, the strain is more nearly equally distributed from the central point of the engine outwardly, by thus dividing the gearing into two trains and driving them as stated; and this will be understood by persons skilled in the art to be an important improvement, and one of particular importance in the construction of engines, such as airplane engines, where the maximum of strength must be attained with minimum weight and with the largest degree of equalization or distribution of strain.

I will next describe the lubricating means and means for cooling the lubricant as it is returned to the crank casing. Leading from the oil pump 13 is a pipe 18 (see Fig. 4) which extends upwardly into the gear area and which has lateral pipes 19 and 20 which carry the lubricant forwardly and rearwardly to the train gearing. In the drawing I have shown a four-cylinder construction. If the construction comprises a greater number of cylinders, the pipes 19 and 20 would be extended forwardly and rearwardly to the outer pairs of train gears. The oil thus discharged from the pipes 19 and 20 flows into the gear chamber and lubricates the gears and returns through the return passages 21 and 22 (see Fig. 2) which connect with the passage 23 within which the shafting 12 rotates and the walls of which passage are the outer walls of the cooling cham-

bers of the adjacent cylinders. A stuffing box bearing 24 in the main casting supports the shaft 12 medially of its length, and passage ways 25 adjacent this bearing permit the oil to flow from the annular passage about the shaft 12 into the crank case area. Thus it will be seen that as the lubricant picks up heat from contact with the gearing and other adjacent parts and flows back through said passage formed in the cooling jackets, the lubricant has cooled as it returned to the crank casing.

I will next describe my improved means for the crown construction and for providing further cooling means. I employ a crown 26 which is secured to the main casting by flanges and flange bolts and which rests down upon the peripheries of the crowns 8. This crown plate has water cooling passages 27 which are connected with the water cooling passages or jackets about the cylinder and to support the casting thus provided with cooling areas the upper and lower webs are lug-connected, as shown at 28. These cooling passages connect with the areas 29 in the crowns 8 by annular openings about the upper portions of said crowns. The upper portions of the crowns 8 extend through bores in the crown plate 26 and are threaded to nuts 29 which hold the same in place. Thus constructed, a cooling medium area is formed in the crown plate which is directly connected with the water jacket system of the engine so that the crowns of the cylinders and the lubricating area are also directly cooled.

Referring now to Fig. 5, I will describe the port construction. The inlet port manifold is shown at 30 and the exhaust port manifold is shown at 31. From the manifold 30 inlet ports 32, 33 and 34 lead to the several inlet openings in the outer walls of

the valves. To the exhaust manifold 31 the passages 35, 36, and 38 lead from said members. The rotating sleeves of the valves 9 have the window openings 39 so positioned that their registration with the inlet ports and the exhaust ports will be properly synchronized to the four-cycle action of the engine. By this construction I arrange my inlet and exhaust manifolds symmetrically upon opposite sides of the engine, and thereby secure compactness, symmetry, and substantially equal balance of parts,—that is to say, by this improved construction I secure a compact and balanced arrangement which is of particular importance in airplane engines.

Having thus described my invention, I claim:—

In an internal combustion engine, the combination of a cylinder, a crown piece extending into the head end of the cylinder, said crown piece projecting at its outer end beyond the head end of the cylinder and having double walls forming a water space therebetween, the inner wall terminating in a spark plug socket, an outer water jacket having double walls, secured to the head end of the cylinder and spaced therefrom to form an oil chamber around the outer end of the crown piece, the inner wall of the jacket being connected to the outer wall of the crown piece and having openings registering with the water space of the crown piece and affording communication with said space and the outer wall of the jacket being connected to the outer end of the spark plug socket, and a rotary sleeve valve between the crown piece and the cylinder and provided with a gear in said oil chamber.

RICHARD C. YATES.
